UNITED STATES PATENT OFFICE.

ANDERS PEDER JENSEN, OF NORRKÖPING, SWEDEN, ASSIGNOR TO B. & O. LIBERGS FABRIKSAKTIEBOLAG, OF ROSENFORS, SKOGSTORP, SWEDEN.

ADJUSTABLE WRENCH.

1,234,169.

Specification of Letters Patent. Patented July 24, 1917.

Application filed May 18, 1917. Serial No. 169,459.

To all whom it may concern:

Be it known that I, ANDERS PEDER JENSEN, a subject of the King of Denmark, residing at Norrköping, in the Kingdom of Sweden, have invented a new and useful Improvement in Adjustable Wrenches, of which the following is a specification.

This invention refers to an adjustable wrench of the kind in which the movable jaw of the wrench is actuated by means of an eccentric device pivoted to the movable jaw and coöperating with lugs on the shank of the rigid jaw.

The object of the invention is to provide an adjustable wrench of the said kind in which there is no lost motion and which may be rapidly and easily adjusted by a single manipulation and be securely tightened around nuts of very different sizes, besides which the wrench needs not be removed from the nut in order to be turned around the same, but when turned back the wrench automatically releases the nut and when turned forward it again automatically 25 grips the nut. The present wrench is also arranged in such manner that it may be taken apart and assembled without having to detach or to secure any connecting part, that is to say that the taking apart and the 30 assembling are simply effected by separating the parts from one another, or by arranging the parts in each other.

The invention is chiefly characterized by this that the eccentric is arranged on a handle pivoted to the movable jaw in such manner that the handle is movable in the plane of the shank and the jaws, so that the force to be exerted for turning the handle and closing the jaws will lie in the same plane as the force exerted for turning the wrench. The pivot pin of the handle in the movable jaw may suitably be on the same side of the shank of the rigid jaw as the working surface of the movable jaw, while the handle 45 extends to the other side of the shank, by which it is attained that the force exerted on the movable jaw, becomes directed as nearly as possible at right angles to the working surfaces of the jaws and through 50 the axis of the nut engaged by the jaws.

The accompanying drawing illustrates an embodiment of the present wrench, viewed from the side and partly in section in Figure 1, and edgewise in Fig. 2.

1 is the rigid jaw of the wrench, which

is preferably made in one piece with the shank 2. The movable jaw 3 may slide along the shank 2 and may be connected with the shank by means of a sleeve 5 embracing the shank and secured to the jaw 3 by means 60 of rivets 4. A handle 6 is rotatably connected with the movable jaw 3, which handle embraces the shank with two parallel lateral projections 7 which extend over the shank 2 and are connected on the side of 65 the shank opposite the handle 6 by means of a pin 8 loosely introduced in a slot 9 in the movable jaw 3. The handle 6 is thus rotatably connected with the movable jaw 3 and at the same time securely held in its 70 appointed position.

On both sides of the shank 2 there is a number of parallel notches 10 arranged above each other in the longitudinal direction of the shank, and each of the lateral 75 projections 7 on the rotatable handle 6 is provided with an edge 11 eccentric in relation to the axis 8 of rotation of the handle. As will be seen from Fig. 2, the edges 11 of the projections 7 are bent inward against 80 the shank 2 so that they will securely engage the notches 10.

The described adjustable wrench is used in the following manner: When the jaws 1, 3 are to be adjusted for instance for a nut 85 12, the handle 6 is turned outward from the shank 2, until the eccentric edges 11 leave, that is to say, become free from the notches 10. Only in this position of the handle 6 can the same and the movable jaw 3 be freely 90 moved along the shank 2, such free movement being impossible while the said edges 11 engage the notches 10 (see Fig. 2). The jaw 3 is then moved to a position which about corresponds to the size of the nut, and the wrench having been placed on the nut, the handle 6 is forced toward the shank 2. The eccentric edges 11 then enter the two nearest notches 10 and force the movable 95 jaw against the nut, which is thus seized 100 between the jaws. When a nut is to be drawn very tight, the force exerted on the handle 6 becomes correspondingly greater, and thus also the grip around the nut more powerful in a corresponding degree. 105

It will be understood from Fig. 1 that the notches 10 and the eccentric edges 11 of the handle 6 are so arranged with relation to the axis 8 of rotation that the movable jaw 3 may be moved within certain limits 110

along the shank by turning the handle also while the eccentric edges are in engagement with the notches. On account hereof, when the wrench is to be moved from one pair of 5 opposing surfaces of the nut to the next pair of surfaces, the wrench may simply be turned around the nut in the desired direction while releasing the hold on the handle 6, after which the handle is again forced 10 against the shank 2.

It is obvious that each pair of notches 10 may correspond to several different sizes of nuts dependent on the position of the handle 6, or of its eccentric edges 11 with relation to the notches 10, and that a comparatively short wrench may be used for comparatively very varying sizes of the nuts, and also that the wrench may be provided with a great number of notches. It is also obvious 15 that there is no lost motion worth mentioning in this adjustable wrench.

As stated above, this adjustable wrench may very easily be taken apart and reassembled without any connecting parts having 20 to be detached or secured. For this purpose the handle 6 is only turned out from the shank 2 so that the eccentric edges 11 leave the notches 10. The shank 2 with the rigid jaw 1 may then be directly pulled out from the sleeve 5 of the movable jaw 3, after 25 which the handle 6 is separated from the jaw 3. The assembling is made in the reversed order.

The details of the described embodiment 30 may be modified without departing from the principle of the invention. The handle 6 may thus, for instance, be provided with

only one lateral projection 7 and one eccentric edge 11, and thus also the shank 2 with notches or projections only on one side. The 40 wrench may also advantageously be arranged as a pipe wrench.

I claim:

1. In an adjustable wrench, the combination of a shank, a rigid jaw on the shank, 45 lugs on said shank, a jaw movable on said shank and provided on the same side of the shank as its working surface with a slot open toward the shank, a pivot pin journaled in the slot in the movable jaw approximately 50 at right angles to the plane of the shank and the jaws, a handle pivoted on said pin and movable in the plane of the shank and the jaws and extending to the side of the shank opposite that of the jaws, and an eccentric device on said handle adapted to cooperate with the lugs on the shank and means permitting said eccentric device to be disengaged from said lugs when the handle is turned at about right angles to the shank. 55

2. An adjustable wrench comprising a shank, lugs and a rigid jaw on said shank, a jaw slidably mounted on said shank and provided with a pivot pin, a handle pivoted to said pin and provided with flanges adapted 60 to embrace said shank when said handle is adjusted to raise said slidably jaw, eccentric devices struck up from said flanges and adapted to engage said lugs to bind said jaws about the object to be clamped, and means 65 permitting said eccentric devices to be disengaged from said lugs when said handle is turned at about right angles to said shank. 70

ANDERS PEDER JENSEN.
